ABSTRACT OF THE DISCLOSURE

A cigarette or cigar holder and/or extinguisher consisting of a frame member that can be used separately or attached to or placed in an ash tray wherein the holder and extinguisher consists of at least one elongated semicylindrical trough presenting an upwardly opening groove for receiving the unlit portion of a burning cigar or cigarette and having a short axial extension consisting of a bimetallic thermostatic material, and a cover for the trough consisting of a similar semi-cylindrical member arranged to underlie the trough when not used for extinguishing, in such a position that an extension of the thermostatic member bears substantially radially against the external surface of the cover to prevent a spring attached thereto from rotating the cover to an inverted position above the trough and in contact with the same at mating edge portions thereof. The frame has guide tabs at the ends of the trough to guide the covers during rotary movement and one edge of the cover includes a radially extending lip for engaging an edge of the trough to limit the rotary travel of the cover.

This invention is a novel device for holding and retaining a cigarette or cigar which incorporates the novel safety feature of a bi-metallic thermal element means, which upon being heated by a burning cigarette or cigar releases a rotatable cover that automatically clamps over and retains the cigarette or cigar in its holder and then automatically snuffs-out the burning cigarette or cigar if it is not removed within a short time.

Briefly, this invention consists of one or more tray-like or trough-like holders for receiving and holding either a cigarette or cigar when placed therein, a bi-metallic thermal element similarly shaped as and attached to one end of each said holder, and a rotatable cover for each holder, which is held in its open position rotated underneath its respective holder against the force of a spring means that tends to rotate and close same, by the frictional force and pressure of said bi-metallic thermal element while it is relatively unheated and pressing against said cover. The cover snaps closed over said holder and over the cigarette or cigar therein to retain and clamp it in the holder whenever the said bi-metallic thermal element becomes sufficiently heated by the burning or heated portion of said cigarette or cigar and expands sufficiently to release the cover.

The essence of the invention which constitutes the novel improvement in holding and retention devices for cigarettes or cigars is the aforesaid novel safety feature consisting of the bi-metallic thermal element which automatically holds open, while relatively unheated, or releases, when heated, a rotatable cover which retains and automatically clamps and snuffs-out a burning cigarette or cigar.

It is, therefore, one object of this invention to provide a means of holding and automatically retaining, clamping and snuffing-out a burning cigarette or cigar.

It is another object of this invention to provide a simple light-weight, inexpensive, cigarette or cigar holder

2

with an automatic retaining, clamping and snuffing feature that can be adapted, attached or clamped to or incorporated as a part of any existing or newly fabricated ash tray or cigarette or cigar holding device.

It is still another object of this invention to provide a simple, inexpensive, lightweight positive safety means to automatically retain, clamp, and snuff-out a burning cigarette or cigar placed in a holder, so that the burning cigarette or cigar when unattended will not continue to burn and drop out of the holder onto furniture, rugs, floors or other surfaces to cause damage or fire.

It is yet another object of this invention to provide a safety device for automatically retaining and clamping a burning cigarette or cigar in a holding means so that the cigarette or cigar can be removed therefrom without damage by simply pulling it out of the holder by its unlighted end.

It is still a further object of this invention to provide a positive safety device which can be used to deliberately extinguish or snuff-out and unattended burning cigarette or cigar placed in a holding means so that the burning cigarette or cigar may be left therein without danger and without the smoker's attention having to be diverted from other operations or endeavors, such as the operation of any land, sea or air vehicle.

A further object of this invention, which is an obvious adaptation thereof, is to provide a simple, positive means whereby any material that is shaped substantially similar to the holder in which it is placed or riding, such as any metallic, plastic, or other material rod, wire, bar, strip or other form, can be automatically clamped and/or retained therein whenever a heated portion thereof sufficiently heats, or otherwise releases, an automatic means which actuates and releases a retention or clamping means to clamp or retain the material in the holder. Such a device can be useful in steel mills, material handling operations, machine tooling, and many other obvious applications, too numerous to set forth, as a safety device and material holding means.

These and still other objects, advantages and uses will become apparent from reading the following description and drawings.

The drawings presented herein, which show the invention, are briefly described as follows:

FIG. 1 is a perspective view of a device constructed in accordance with the present invention.

FIG. 2 is a transverse cross-sectional view of the FIG. 1 device taken along line 2—2.

FIG. 3 is a front elevation view of the FIG. 1 device.

FIG. 4 is a vertical, longitudinal cross-sectional view of the device shown in FIG. 1 and includes a view of the FIG. 7 mounting means adhered to the subject device.

FIG. 5 is a fragmentary horizontal cross-sectional view of the FIG. 1 device along the lines 5—5 of FIG. 3 showing one means of fastening the bi-metallic thermal element to the body of the subject device.

FIG. 6 is a perspective view of the bi-thermal element with the relative unheated (closed) and heated (open) positions illustrated.

FIG. 7 is a perspective view of one type of mounting means, and deformable tab portion for use in mounting the subject device to a suitable supporting surface.

FIG. 8 is an inverted perspective view of another mounting means similar to that of FIG. 7 which is clipped onto the bottom of the FIG. 1 device.

The invention, as generally shown in the aforesaid drawings, will be better understood from the following description.

The invention and the subject novel device is generally shown in FIG. 1. This device consists of a means for holding and automatically retaining and/or clamping

anything placed or riding therein, as for example a cigarette or cigar 2 as illustrated in FIG. 1. As illustrated, it consists of a generally rectangular, box-like frame 3, preferably fabricated or moulded from one piece of any suitable strip material, such as aluminum, steel, plastic or other conventional suitable material, for manufacturing simplicity and economy, having a bottom 6, upturned sides 4 and ends 5.

The said sides are turned or formed inwardly towards each other across the top of the frame and formed into one or more substantially trough-like holders, illustrated as 8 and 9 in FIGS. 1, 2 and 3. These trough-like holders are preferably of a cross-sectional shape that is similar to that of the material held therein. For example, where the device is used for a cigarette or cigar each holder is preferably substantially semi-cylindrical and sufficiently elongated to hold the cigarette or cigar. Each holder may either be slightly smaller in diameter than the cigarette or cigar, or be approximately the same diameter, so that the cigarette or cigar will fit snugly therein.

Preferably each side 4, at the same one end thereof, is fabricated, moulded or extended to form a tab, which are respectively shown as 10 and 11. These may be used as a fastening means for attaching the bi-metallic thermal elements 12 and 13 to the frame. For example, each tab may be turned outwardly and pressed backwardly against the side 4 to hold and support stem 14 or 15 of the respective bi-metallic thermal element 12 or 13 therebetween, as shown in FIGS. 1, 3, and 5. It is obvious, however, that the bi-metallic thermal elements may be attached to the frame by any other conventional fastening means.

The ends 5, in the design illustrated, are upturned and cut to a desired height, preferably to be approximately equal to the height of side 4. Each half of each end is stamped, cut-out or otherwise formed into a cross-sectional form 16 which is similar to that of the respective adjacent holder overlying it, as shown in FIGS. 1, 2 and 3. The edge of this cut-out portion serves to cradle and to provide a bearing surface for the respective rotatable covers 17, 18. Each cover is made slightly longer than the distance between ends 5 and extended slightly past the bearing surface 16 of each end, as shown in FIGS. 1 and 4.

The cross-sectional shape of each rotatable cover 17, and 18 is substantially similar to the cross-sectional shape as its respective holder 8 or 9. Where the device is used for cigarettes or cigars, the covers are preferably substantially semi-cylindrical in shape, with the length and diameter approximately equal to that of its respective holder. Each cover is designed to rotate and fit over its respective holder and to fit over and around the top portion of a cigarette or cigar in the holder, in order that the cigarette or cigar will remain clamped in the holder when the cover is in its closed position. Each cover is also designed to rotate and fit underneath its respective holder when it is in the open position.

Along each end edge of holder 8 and 9, located as desired, but preferably near the end of each corner thereof, are fabricated, moulded or formed tabs 19. These tabs are turned or bent downwardly towards the respective end 5 bearing surface 16 into a plane that is substantially parallel to end 5. This permits the tabs to straddle and to retain therebetween each respective cover 17 or 18. This keeps each cover cradled upon the bearing surfaces 16. These tabs, however, are not turned or bent against the ends of covers 17, 18 but instead are stopped short thereof. This provides sufficient clearance therebetween to permit the free rotational movement of each cover.

Spring means 20 and 21, of suitable material and design, are loosely attached to each respective cover 17 and 18 at tangs 22 and 23, as shown in FIG. 2 and 3. This loose attachment permits each cover to freely rotate without the spring hindering the rotation. Each tang 22 or 23 is preferably located near the outer edge, mid-point

of each respective cover, when it is in its open position. Each spring means 20 and 21 is stretched and attached diagonally opposite to bottom 6 from where it is attached to the respective cover. They are attached to the bottom at respective tangs 24, 25 as shown in FIGS. 2 and 3.

These tangs are located near the outer side edge of the bottom about its longitudinal mid-point. The position of tangs 22, 23 and respective tangs 24, 25 are sufficiently offset from one another so that the action of either spring means 20 or 21 will not interfere with the action of other.

When spring means 20 is stretched and attached between tangs 22 and 25 a positive tensional force is created which tends to close cover 17 by rotating it counter-clockwise over holder 8. Likewise, when spring means 21 is stretched and attached between tangs 23 and 24 a positive tensional force is created which tends to cause cover 18 to rotate clockwise and close over holder 9. This action is illustrated by arrows in FIG. 3, with cover 18 shown both in its open position, rotated underneath holder 9, and in its closed position 18', rotated clock-wise over and covering holder 9. Arrows in FIG. 1 also illustrate the rotational action of covers 17 and 18 upon closing.

Each respective cover 17 or 18 is held in its open position rotated underneath its respective holder 8 or 9, against the force of its respective spring means 20 or 21 attached thereto by the frictional force or pressure of projection 26 of the respective bi-metallic thermal element 12 or 13 being pressed against the adjacent surface of the cover while the particular bi-metallic thermal element is in its relatively unheated state. As the bi-metallic thermal element becomes sufficiently heated by either a burning cigarette or cigar, or heated portion of other material, in the respective holder adjacent thereto and expands, the pressure of projection 26 against the cover becomes sufficiently released to a point where the force of respective spring means 20 or 21 cause the respective cover 17 or 18 to snap closed. The relative position of the bi-metallic thermal element in its relatively unheated, or contracted, and relatively heated, or expanded, states is shown in FIGS. 3 and 6 respectively as 13 and 13'.

For some applications, it may be desirable to have a tip portion 27 slightly wider than and at the end of projection 26. Such a tip may be turned or bent inwardly towards the surface of the respective adjacent cover 17 or 18 so that the edge of the tip will contact the surface of the cover to hold it open while the respective bi-metallic thermal element is unheated and pressing it against the cover.

The area of contact 28 on the surface of each cover, which either projection 26 or tip portion 27 contacts may either be a smooth, roughened or knurled surface, as desired and appropriate. It has been found that this area of contact should be either roughened or knurled. This permits a more positive and easier holding by either projection 26 or tip 27.

Each rotatable cover 17 or 18 is preferably fabricated, moulded or formed with a substantially right angular lip 29 disposed longitudinally along the edge thereof which is nearest to bend 7 in the frame 3 when the cover is in its closed position. The mating of lip 29 and bend 7 on closure of cover 17, 18 forms a snug, relative air-tight seal to exclude air from any burning cigarette or cigar or other material clamped between cover 17 or 18 and respective holder 8 or 9. The exclusion of air, combined with the condensation or chemical reaction which occurs causes the burning cigarette or cigar to be extinguished within a short time. This eliminates the danger presented when an unattended burning cigarette or cigar is left in the holder.

Lip 29 is also used as a handle means for the user to rotate the cover open and cock it open against the holding pressure of the respective bi-metallic thermal element 12 or 13, when the element is in its relatively unheated or contracted state.

In designing the subject device, the substantially semi-circular cross-sectional form of each cover is extended a sufficient number of degrees beyond a true 180° semi-circular form. This permits each cover when closed to remain partially encircled underneath its respective holder 8 or 9 and to remain retained longitudinally by tabs 19. Without this feature, the cover 17 or 18 when it snaps closed would flip out of place and escape being properly cradled within bearing surface 16 and being straddled and retained longitudinally by tabs 19.

Bi-metallic thermal element 13, which has the same form as element 12 except for it being oppositely or reversibly disposed in form, is more particularly shown in FIG. 6. This shows the main portion thereof to be substantially semi-cylindrical in shape with a trough-like recess. Preferably the cross-sectional shape of the element's main portion should be substantially equal to the cross-sectional shape of its respective adjacent and abutting holder 8 or 9. It should be noted, as shown in FIGS. 3 and 6, that the main portion of each bi-metallic thermal element preferably has a bulged portion 30 near its end, so that better action and a better pressure contact may be maintained with the surface of the respective cover 17 or 18. A stem 15, as shown preferably parallel to the nearest side 4, is provided as a part of each bi-metallic thermal element as a mounting leg and support for mounting and fastening the element to side 4 by either tab 11 or other fastening means.

FIG. 6 further illustrates the relatively unheated, or contracted, position of the bi-metallic thermal element 13, as well as the relatively heated, or expanded, position 13' of same. As the burning portion of a cigarette or cigar, or the heated portion of any other material, in holder 9 comes close enough to the bi-metallic thermal element 13 to relatively heat it, the element progressively expands. As this expansion occurs, the holding pressure of the thermal element's projection 26 or tip 27 against the surface of cover 17 progressively lessens to a point where the pressure is insufficient to hold the cover open against the force of spring means 21 attached thereto and the cover rotates and snaps closed over holder 9.

The bi-metallic thermal element may be made from any conventionally suitable material. In fabrication, bend 31, as shown in FIG. 1, 2, 3 and 6, is preferably made in the thermal element to facilitate it to fit over the edge of the cut-out portion 32 of side 4. Further, stem 14, 15 preferably has a cutout or notched portion 33 to accommodate the respective tab fastening means 10 or 11. Both of these features provides a more rigid support in mounting the element. Shoulder 34 of said notch is preferably designed to fit against the top of tab 10 or 11 for added rigidity.

It has further been found preferable when using two holders 8, 9 and respective covers 17, 18 together that they be in substantially aligned parallel positions and to provide the rotational action of each cover to be inside to outside, i.e. cover 17 to rotate counterclockwise and cover 18 to rotate clockwise.

It is further obvious that the subject device may be made with one or any number of respective holders and covers for use with one or more cigarettes and/or cigars at a time, without detracting from the spirit and concept of this invention. Furthermore, the respective holder and cover combinations may either be arranged in the same plane substantially parallel to each other or be stacked or arranged in any other position as best suits the particular design purpose and application.

FIG. 7 shows a means 35 for mounting the subject device. This consists of a portion of suitable conventional strip material formed with a tab portion 37, which can be easily bent and formed by hand to conform to the surface shape of any thing upon which the subject device is desired to be mounted. This mounting means has a support portion 36, which is shaped substantially similar to the underneath side of bottom 6. This support may be at-

tached to the underneath side of bottom 6 by the use of any suitable conventional adhesive 38, as shown in FIGS. 4 and 7, or by any other suitable conventional fastening means. Tab 37 may be adhered or fastened to the particular surface upon which the device is mounted.

FIG. 8 shows a preferred alternative means of attaching mounting means 35 to bottom 6. This consists of having support portion 36' made into a clip-type means of attachment. This is preferably accomplished by having slits 39 along each edge of support portion 36 leaving clip tabs 40 along each edge. The clip-tabs are designed to slip through appropriate open spaces 43 in ends 5 so as to clip over and above the upper surface of bottom 6. Thus, the main portion 41 of the support 36 is clipped underneath bottom 6 while tabs 40 are clipped over and above the outside portions of bottom 6. The resiliency between portion 41 and tabs 40 creates a spring clip-type of mounting which holds the subject device in place on mounting means 35.

It may also be desirable to make the length of tabs 40 longer than the length of bottom 6 so that the ends thereof stick out beyond the bottom. They then can be bent or turned down and back under and against bottom 6 to form a positive means of retaining device 10 in mounting means 35.

The clip-type of mounting means described above is preferred since this permits the easy removal of device 10 from its mounting whenever desired for cleaning, repair or other purposes.

Tab 37, as shown in the application illustrated by FIG. 4, is deformed by hand to fit the contour of the mounting surface. It is shown here adhered to the edge surface of any ash tray 40. This particular illustration shows a reverse rolled or ridge portion 41 formed in the deformable tab 37. This has been found advantageous to give added support in mounting the subject device. However, it is obvious, and sometimes preferable, that no roll or ridge portion 41 be used and that the tab 37 be adhered or fastened directly to the inside edge surface of an ash tray or other mounting surface.

It will also be obvious to those skilled in this, as well as those skilled in various other arts, that numerous variations and adaptations may be made in the subject device without departing from the spirit and concept of this invention. Therefore, this invention is not considered to be limited to or by that illustrated and described herein.

What I claim as my invention is set forth in the following claims:

1. In a device for holding cigarettes or cigars, or other material, the combination of a frame, at least one trough-like holder which forms substantially the top portion of said frame for holding a cigarette or cigar, or other material, a bi-metallic thermal element, with a trough-like recess of similar transverse cross-sectional shape as the trough-like holder, attached to the frame and mounted with said trough-like recess juxtaposed next to and forming a longitudinal continuation of one end of said trough-like holder, a trough-like cover of similar transverse cross-section shaped as and for each trough-like holder, mounted to rotate underneath the trough-like holder leaving the top of the holder open for receiving a cigarette or cigar or other material in its open position to be rotated over and enclose the top of said trough like holder while a portion of the said cover remains under the holder in its closed position, a spring means attached to each cover and diagonally to said frame which tends to cause said cover to be rotated to a closed position, and a projection of said bi-metallic thermal element contacting under pressure the surface of said cover, while the element is relatively unheated, to hold the cover open against the force of said spring means until said element sufficiently expands, after being relatively heated by the heat from a portion of a cigarette or cigar or other material in said holder, and to release said

cover to rotate and snap closed under the force of said spring means.

2. The same device as claimed in claim 1 wherein more than one holder, respective cover and respective bi-metallic thermal element is aligned substantially parallel to each other in substantially the same plane.

3. The same device as claimed in claim 1 wherein the trough-like holder and cover is substantially semi-cylindrical.

4. The same device as claimed in claim 1 wherein said frame is substantially rectangular, box shaped having a bottom, sides, ends, and the aforesaid top, all formed of one piece of strip material.

5. The same device as claimed in claim 1 wherein a stem portion of each bi-metallic thermal element is attached to the frame via a tab fastening means, which consists of an extended portion of the end of each side nearest to said element bent back and against the side with a portion of said element held therebetween.

6. The same device as claimed in claim 5 wherein said stem has a notched out portion for receiving a fastening means.

7. The same device as claimed in claim 5 wherein said stem portion is substantially parallel to side to which it is attached.

8. The same device as claimed in claim 4 wherein the upper portion of each end is shaped to be substantially similar in end elevational transverse cross-sectional shape as said top, with a vertical and longitudinal clearance space between said top and each end.

9. The same device as claimed in claim 4 wherein the rotatable cover in its open position is cradled underneath its holder, with a clearance space there-between, and each end having a cut-out portion providing an upper edge which in transverse cross-sectional shape is substantially similar to the transverse cross-sectional shape of said respective holder for supporting said cover.

10. The same device as claimed in claim 9 wherein a portion of each end of the holder is extended to form a tab which is turned downwardly to be in a substantially vertical plane and to straddle and to retain the rotatable cover, while leaving sufficient clearance between said tab and said rotatable cover to permit the free rotational movement thereof.

11. The same device as claimed in claim 1 wherein the cover has an angular lip portion disposed outwardly thereof and longitudinally along the cover's edge which bears against the edge of its respective holder when the cover is in its closed position.

12. The same device as claimed in claim 4 wherein a mounting means, with a hand deformable protruding tab portion for use in hand conforming to a mounting surface and attaching the device to any surface, is attached to the underneath side of the bottom.

13. The same device as claimed in claim 12 wherein the mounting means is adhered to the underneath side of said bottom by suitable adhesive.

14. The same device as claimed in claim 12 wherein said mounting means is clipped to said bottom, with one portion thereof shaped to be substantially similar to said bottom shape with longitudinal slits near to and along its outer edges leaving a longitudinal tab along each outer edge thereof as a clip portion to be slipped though an opening in one end, nearest to the end of the frame where the bi-metallic element is mounted, and to clip over the top surface of said bottom while the remaining portion thereof between the said tabs clips underneath the said bottom and with the other portion thereof sufficiently extended beyond said bottom as a protuding, hand deformable tab, which tab is hand formed to fit and is attached to any surface upon which it is desired to mount the device.
